UNITED STATES PATENT OFFICE.

ORA L. LANCE, OF LOS ANGELES, CALIFORNIA, ASSIGNEE TO ROYAL GUM COMPANY,
OF LOS ANGELES, CALIFORNIA.

VENDING-MACHINE.

1,153,692.

Specification of Letters Patent. Patented Nov. 2, 1915.

Application filed September 30, 1914. Serial No. 864,290.

To all whom it may concern:

Be it known that I, ORA L. LANCE, a citizen of the United States, residing at Los Angeles, in the county of Los Angeles, State 5 of California, have invented new and useful Improvements in Vending-Machines, of which the following is a specification.

My invention relates to that type of vending machines which are operated by use of 10 a coin and in which the gum, candy or other articles to be vended, are of globular shape.

The object of my invention is to provide 15 a machine that can be economically manufactured, which embodies an improved device for delivering the articles vended to the customer.

A further object of my invention is to combine the mechanism with a registering device, whereby each time the machine is 20 operated, the sale will be automatically registered, showing at a glance the number of times the machine has been operated.

Further objects and advantages will be 25 hereinafter referred to and pointed out.

Referring to the drawings: Figure 1 represents a side elevation of the exterior of 30 the machine. Fig. 2 represents the base of the machine as seen from above, the dotted lines representing the interior mechanism.

Fig. 3 is a sectional view of the base of the machine at dotted lines "a—a" Fig. 2. Fig. 4 is a sectional view of that part of the machine between dotted lines "b—b" Fig. 2. Fig. 5 is a sectional view of that part of the 35 dial and mechanism shown at dotted lines "c—c" Fig. 3. Fig. 6 is a front view of that part of the dial and mechanism represented in Fig. 5 as would be seen with the outer casing "C" removed.

Referring to the different views, similar 40 reference letters designate similar parts.

"A" represents a glass receptacle which contains the articles to be vended.

"B" represents a metallic base in which 45 the mechanism is contained, and onto which the glass receptacle "A" is firmly fastened and held by a metallic band indicated by "D", which is provided with a hinge indicated by "e". Said band is provided, 50 with an adjusting screw, "a", and is adapted to be fastened in its adjusted position by a padlock means represented by "b".

"C" indicates the outer surface of the dial which contains the coin conveying mechanism. 55

"E" indicates the lever for operating the machine.

"F" indicates the registering device which is inclosed in the dial and shows the number of times the machine is operated. 60

"G" indicates the place where the coin is inserted.

"H" shown in dotted lines, indicates a 65 slidable plate held flush with the inner face of the top of the base "B".

"I" indicates a receptacle to receive the coins.

"J" indicates a shield protecting an opening, indicated by "L", in the top of cylinder represented by "s". 70

"K" indicates the flanged end of the brace "m" which in fact, is a continuation of cylinder "o".

"M" indicates a device for fastening the vending machine to a standard, the top of 75 which is represented by "N".

Describing more fully the functions of each part indicated, the glass receptacle "A" is provided with a flanged base by means of which same can be fastened in its 80 place by the metallic band "D" closing over it and fastened by set screw "a" and locked by padlock "b".

The top of the base "B" slants toward the center, at which place there is an opening 85 for the articles vended to pass through and into a cylinder "g" which is a part of the slidable plate indicated by "H". Said slidable plate is also provided with two upward extending pins indicated by "d" 90 and "d'" which serve to agitate the articles to be vended so that they are free to roll into the receptacle "g". Said sliding plate "H" is also provided with a depending plate "h" shown in Fig. 4 and in section in Fig. 95 3. Said depending plate "h" is provided with a slot means "r" which receives the end of a lever "k" which serves to slide same. The slidable plate "H" is held in its position by guards "e" and "e'". The cylinder "o" is provided with another cylinder "s" which extends at right angles from same and into which the articles to be vended pass when slidable plate "H" is operated 100.

to its extreme position. The article is then conveyed through cylinder "o" to a receiving cup "p" where same is delivered to the customer.

5 The dial Fig. 5 and Fig. 6 contains the mechanism which is unlocked and controlled by the insertion of a coin indicated by "g". It consists of an outer casing, the front of which is represented by a curved face "C" 10 and the back of which is composed of a plate represented by "j". The mechanism contained within said dial consists of a disk, "w", provided with a lever "E" which extends outward from the dial through a slot and is adapted to turn to the position shown by dotted line in Fig. 6. The mechanism which is directly operated on by the coin consists of an arm "j", which is provided with a spring "h". Said arm "j" 15 serves the purpose of a lock which engages the coin slot in the disk "w" and prevents the same from being operated unless a coin has been inserted.

"x" indicates a lug flush with, and forming a part of disk "y". The function of said lug is to operate lever "f" by coming in contact with the end of said lever indicated by "m" which moves said lever which is pivotally held in lug "c" and serves to 20 dislodge the coin which drops through the space at "b" into the coin receptacle indicated by "I".

To prevent the dial from returning to its original position after a coin has been inserted and partly turned, but before the coin has been dislodged, I have provided a spring catch, "q", which is equipped with a coil spring "r" and which is adapted to engage notches in the disk "w" indicated by "n", 25 and prevent same from returning until the handle "E" has been turned to its extreme position, and the large notch "o" has reached a point opposite the spring catch "q", which allows said catch "q" to resume its original position after which the mechanism will all be returned to its original position by coil spring "s", shown in Fig. 4.

Within the dial is a registering device of 30 the ordinary style which is operated by a spring hook indicated by "a", which engages one of a series of notches indicated by "t" in said registering device.

To prevent the registering device from 35 moving from its adjusted position, I have provided a catch means "z" which engages said notches "t". Said catch means is equipped with a spring "y".

The operation of the machine as described 40 consists of inserting a coin in slot "G" and pulling down lever "E", which shifts sliding plate "H" in a longitudinal movement, carrying with it two of the small spheres of gum, candy or the like to be

vended to a point directly above the opening "L" in cylinder "s" where one of the small spheres will drop through the opening "L", and as the mechanism is returned to its original position by means of coil spring "t", the small sphere which has dropped through the opening "L" will be conveyed by means of depending arm "r" into the cylinder "o" where it will roll into a cup "p" from which the customer can remove it. The object of having means for carrying two spheres in cylinder "g" is that in case a new sphere fails to drop into a cylinder "g", on each operation there will be a reserve of one sphere in said cylinder "g". As the lever "E" is pulled down it carries with it the coin which after being deposited in slot "G", comes in contact with arm "j", raising same and preventing it from engaging the slot which carries the coin in disk "w" which would prevent the mechanism from being operated. The dial is prevented from returning to its original position until after coin has been dislodged by means of spring catch "q", which engages notches "n". When the dial has been turned to its extreme position, the lug "x" rigidly fastened thereon strikes the end "m" of lever "f", whereupon the opposite end of said lever strikes the coin, dislodging it through opening "b". When the lever is now released the mechanism will return to its original position, ready for another operation. The money receptacle "I", which may be locked in any preferred manner, within the base "B" of the machine, is equipped with a device "M" for fastening same on a pedestal. In order to lock same on the pedestal I have provided a slot "v" through which a staple may be placed and a padlock inserted.

I claim:

1. In a coin controlled apparatus; the combination of a disk having an operating lever integral therewith and offset with reference to the disk, a casing having a slot in one side through which said lever extends, a cam lug rigidly secured to the outer face of said disk, a lever pivotally mounted in said casing and adapted to dislodge the coin, one end of said lever being engaged by said lug, a recess in said disk to receive a coin, an arm provided with a cam lug which serves as a detent, it being mounted at one end by a stud pin to the casing, a spring to coact therewith and cause said arm to engage said coin recess and prevent further advancement of the disk unless raised by the cam action of a coin, and means to prevent the disk from being returned until a full stroke has been made.

2. In a coin controlled apparatus; the combination of a disk having part of its outer margin extended to form a lever, a

casing consisting of a front and back section, a shaft being journaled in the back section and to one end of which is secured said disk, an opening in the top of said casing to receive a coin, an opening in the back section of the casing to allow a coin to be dislodged therefrom, a receptacle to receive the

coins, a slot in the side of said casing to allow the lever from the disk to extend and be given a full downward stroke.

ORA L. LANCE.
